UNITED STATES PATENT OFFICE

PAUL M. HOENSHEL, OF PORT MAYACA, FLORIDA, ASSIGNOR TO MAYACA COMPANY, OF MIAMI, FLORIDA, A CORPORATION OF FLORIDA

COMBINED IRRIGATION AND DRAINAGE PUMP

Application filed July 21, 1930. Serial No. 469,441.

This invention relates to a combined irrigation and drainage pump.

An object of my invention is the construction of a very efficient and relatively inexpensive pump for use in irrigating land or, if desired, for draining land.

Another object of my invention is the construction of the body of the pump-casing which is provided with efficient and novel means whereby one side or part of the casing may be removed for allowing water to more freely enter the casing.

A still further object of my invention is the construction of a novel rod-screen at the bottom of the pump casing for increasing the efficiency of my pump.

A still further object of my invention is the novel arrangement of the bracing beams and the novel construction of the thrust bearing, etc.

This application discloses valuable improvements over my prior United States Patent No. 1,737,372, "combined irrigation and drainage pump."

With the foregoing and other objects in view, my invention comprises certain novel constructions, combinations and arrangements of parts as will be hereinafter fully described, illustrated in the accompanying drawings, and more particularly pointed out in the appended claims.

In the drawings:

Figure 1 is a vertical, central, sectional view of my pump while

Figure 2 is an enlarged top plan view of the same.

Figure 3 is a sectional view taken on line 3-3, Figure 1, and looking in the direction of the arrows.

Figure 4 is a fragmentary view, in side elevation, taken on line 4-4, Figure 3, and looking in the direction of the arrows.

Figure 5 is a sectional view taken on line 5-5, Figure 1, and looking in the direction of the arrows.

Figure 6 is a vertical, central, sectional view of the propeller "tube" or casing, while

Figure 7 is a top plan view of the same.

Figure 8 is an enlarged sectional view taken on line 8-8, Figure 1.

Figure 9 is a vertical, central, sectional view of the slotted sleeve, of the bearing device, while

Figure 10 is a top plan view of the same.

Figure 11 is a perspective view of one of the "needles" or removable boards of the expansion casing.

Figure 12 is a sectional view taken on line 12-12, Figure 1, and looking in the direction of the arrows.

Figure 13 is an enlarged fragmentary, sectional view of the floor, rod screen and propeller casing.

Referring to the drawings by numerals, 1 designates the vertical uprights that are 65 driven into the bottom of the canal; these uprights 1 are creosoted or otherwise treated prior to positioning for increasing their durability and life. Sets of timbers or beams

2 connect the uprights 1 near their upper 70 ends. These beams 3, in each pair, are notched (Fig. 2) to fit upon a corner of an upright 1, and bolts 4 extend through the uprights and the beams 3, securing them together. Therefore, it will be noted that the 75

beams in each pair are spaced apart to allow the vertical propeller shaft 5 to extend therebetween. A bearing box or plate 6 is placed against the beams in each pair 2 and a slight horizontal adjustment of the plate 6, on its 80 supporting beams, is obtainable, for accurate centering of the propeller shaft 5 in my pump, prior to the placing of fastening bolts 7 through plate 6 and its supporting beams 3. I usually employ two bearing devices, of 85 which plate 6 is a part, in my pump, each one resting against a set of said horizontal spaced beams 3.

Each bearing device comprises said plate 6 with an upstanding flange 8, within which 90 flange is a felt washer 9, Fig. 8. A suitable lubricating device 10 is employed for permitting a lubricant to pass into the device. A slotted sleeve 11, wedge-shape in cross section is placed around shaft 5 and a Timken 95 roller bearing 12 is placed against sleeve 11 and within the upstanding flange 8. A thrust bearing collar 13 is secured on shaft 5 against slotted sleeve 11. Various type propellers 14 (Fig. 1) can be used, the exact 100

pitch of the same dependent upon head to be pumper against and speed of pump. A forged steel propeller of six-blade type, brazed into iron hub and keyed on steel propeller shaft 5, suits most conditions, and is shown in Figure 1. I preferably use two bearing devices to take all thrust and radial load, the bottom bearing being merely a guide bearing to prevent whipping of shaft; as 10 herebefore indicated, these bearing devices are mounted on the two sets of diagonal timbers or beams, crossing at right angles and preferably two feet from each other, with pulley 15 mounted on shaft 5 between said 15 two bearings. The slotted sleeve 11 acts as a wedge to lock the bearing to the shaft. The thrust collar 13 is securely held on shaft 5 by set screw 16 to prevent any movement of said tapered sleeve 11. When my pump is to be 20 used reversed, one of the bearing devices is set upside down, as indicated by dotted lines 17, to take the thrust when reversing. When the pump is only used as a lift pump, both bearing devices are set on top of the spaced 25 beams 3 to take downward thrust only.

I form a horizontal floor 18 on the vertical uprights 2 and build an expansion casing 19 around and above said floor. This casing is preferably constructed of boards, 30 although it may be formed of any other suitable material and one side of the expansion casing is peculiarly constructed for allowing the removal of the same for free passage of the water into the expansion chamber formed 35 by said expansion casing 19. This removable side is constructed by placing two vertical cleats 20 against the registering face of two uprights 1 forming part of one side of the pump, as clearly shown in Figures 3 and 4.

40 These cleats form registering, vertical grooves 21 on two of the uprights 1. In these grooves 21 extend the bevelled ends 22 (Figs. 4 and 11) of the "needles" or boards 23. I use the term "boards" in a broad sense, meaning any suitable unit of the specific-like character. The bevelled ends 22 of each board 23 are formed in parallelism to prevent jamming or wedging while placing the board in 45 position or readily removing the same when it is desired to have one side of the expansion casing 19 open. Hook grips 25 are attached to the outer face of and near the ends of each board 23 for allowing the operator to more readily manipulate the boards.

50 In the floor 18 of expansion casing 19, I preferably bore vertical apertures or holes 26, and through these holes 26 I place screen rods 27; these rods 27 are forced a suitable distance into the bottom of the canal (Fig. 1), thereby forming an efficient screen around the propeller "tube" or casing 28. Casing 28 has an angular flange 29 welded thereon at its upper edge; this flange is not only angular in cross-section, but it is annular for 55 rounding the casing 28. The flange 29 is

provided with large vertical holes 30, in which are fitted bolts 31 having shanks of considerable less diameter than the diameter of said holes, so that the propeller casing 28 can have a certain amount of body adjustment upon floor 18 to accommodate the casing to a nicety with reference to propeller 14 and shaft 5; this slight adjustment is indicated by the relative size of the hole 30 and bolt 31 of Figure 13. In the open bottom of casing 28 are secured horizontal vanes 32, to which is secured vertical sleeve 33 (Figs. 1 and 6). In sleeve 33 is suitably mounted shell 34. Shaft 5 extends into shell 34.

Discharge culverts 35 have their inner ends 70 opening into expansion casing 19 any suitable distance above the floor 18. Further, any desirable number of said culverts 35 may be used.

It will, therefore, be understood that I 85 have provided a pump of the class described with a peculiarly constructed removable side; also with a peculiarly constructed screen formed around or "enclosing" the end of the propeller casing for keeping out foreign 90 substances and thereby increasing the efficiency of the pump, and I also have provided peculiarly constructed supporting beam units for allowing the propeller shaft to be accurately centered by means of bearing devices 95 carried on said units.

This pump is a radical improvement over my original pump shown in Patent No. 1,737,372, issued Nov. 26, 1929, though still utilizing the reversible feature and taking the discharge from the bottom of the pump. My pump is now being made in various sizes 100 from ten inches to twenty-four inches in diameter, but the accompanying drawings have been made from the twenty-inch size, which 105 suits most conditions.

The removable side, constituted by said boards 23 is generally formed on the downstream side, so as to permit ready removal when it is desired to drain water from the fields back into the canal through the pump. By these means, the same installation handles water both on and off the land. In reversing, the boards 23 are put in place and the pump direction reversed by reversing the 110 twist in the quarter-turn guide belt 36 (Fig. 1), which causes the pump to thrust water down through the propeller casing 28, the water in the fields flowing by gravity 115 through culverts into the pump, where it is thrust down through the pump. Gates (not shown) on the inside of the field or in the pump are then put in place to prevent water from running back when the pump is stopped.

125 All parts of my pump are easily accessible, and the entire pump can be removed and replaced in a short time, under the most adverse conditions. The expansion chamber in casing 19 eliminates cavitation and excess- 130

sive swirling of water and permits water to be forced through earth-fills by means of culverts, avoiding the expense of concrete work in easily eroded soils. Water rises in 5 the expansion chamber only enough to overcome difference in head and pipe friction, and by using large diameter culverts, this is reduced to a minimum.

My pump can be reversed by reversing the 10 direction of rotation of the propeller ("impeller"); the discharge is at the bottom of pump, and water is never raised higher than necessary; it is designed to handle water directly from the pump into culverts, avoiding 15 all open flumes, etc.; the same installation acts as drainage and irrigation means, and is readily adaptable to special conditions, and is simple in design, making it absolutely dependable, and easily installed and operated 20 by common labor.

While I have described the preferred embodiment of my invention and illustrated the same in the accompanying drawings, certain minor changes or alterations may appear to 25 one skilled in the art to which this invention relates during the extensive manufacture of the same, and I, therefore, reserve the right to make such changes or alterations as shall fairly fall within the scope of the appended 30 claims.

What I claim is:

1. In a pump of the class described, the combination of an expansion casing provided with a bottom, bodily-movable screen rods 35 extending through said bottom and into the bottom of a canal, and propelling means within said screen rods.

2. In a pump of the class described, the combination of an expansion casing provided with a bottom, said bottom provided with vertical holes extending therethrough, bodily-movable screen rods passed through said 40 holes and normally extending into the bottom of a canal, and propelling means in communication with said expansion casing and within the screen formed by said screen rods.

3. In a pump of the class described, the combination of an expansion casing provided with a bottom, a propeller casing having 45 a flange resting on said bottom, said flange provided with large vertical holes, fastening means extending through said holes and into said bottom for allowing body adjustment of said propeller casing on said bottom, and propelling means in said propeller casing.

4. In a pump of the class described, the combination of an expansion casing provided with a bottom, of a propeller casing having 50 an angular flange welded upon its upper end, said flange resting on said bottom, said flange provided with large vertical holes, bolts having shanks of less diameter than said holes and positioned in said holes 55 and bottom, whereby the propeller casing can

have a slight body adjustment on the bottom, and propelling means in said propeller casing.

In testimony whereof I hereunto affix my signature.

PAUL M. HOENSHEL.
